US0D1028253S

(12) **United States Design Patent** (10) Patent No.: **US D1,028,253 S**
(45) Date of Patent: ** May 21, 2024

(54) **DEVICE FOR TRIMMING A MEDICAL ARTICLE**

(71) Applicant: **Smiths Medical ASD, Inc.**, Plymouth, MN (US)

(72) Inventor: **Joseph DeStefani**, San Diego, CA (US)

(73) Assignee: **SMITHS MEDICAL ASD, INC.**, Plymouth, MN (US)

(**) Term: **15 Years**

(21) Appl. No.: **29/757,582**

(22) Filed: **Nov. 6, 2020**

(57) **CLAIM**

The ornamental design for a device for trimming a medical article, as shown and described.

DESCRIPTION

FIG. 1 is a front perspective view of a device for trimming a medical article.

FIG. 2 is a front view of the device of FIG. 1.

FIG. 3 is a back view of the device of FIG. 1.

FIG. 4 is a left side view of the device of FIG. 1.

FIG. 5 is a right side view of the device of FIG. 1.

FIG. 6 is a top view of the device of FIG. 1; and,

FIG. 7 is a bottom view of the device of FIG. 1.

The broken lines in the figure denote portions of the device for trimming a medical article that form no part of the claimed design.

1 Claim, 3 Drawing Sheets
